UNITED STATES PATENT OFFICE.

WILLIAM P. REAVES, OF GREENSBORO, NORTH CAROLINA.

ASTIGMATIC DIAL.

Application filed August 2, 1922. Serial No. 579,235.

To all whom it may concern:

Be it known that I, WILLIAM P. REAVES, a citizen of the United States, residing at Greensboro, county of Guilford, and State 5 of North Carolina, have invented certain new and useful Improvements in Astigmatic Dials, of which the following is a specification.

The present invention relates to eye testing 10 apparatus and particularly to devices of the meridian dial type designed to determine the axis of astigmatism of the eye in its different meridians.

In my copending application Ser. No. 15 558,493, filed May 4, 1922, is disclosed and claimed an eye testing apparatus in which the meridian lines may be varied in thickness as desired, thus avoiding the necessity for using a series of charts having lines inscribed thereon, the lines of the several 20 charts being of different values as measured in visual acuity units.

The object of the present invention is to provide an improved apparatus of the type 25 disclosed in the application above mentioned. In my prior device the meridians comprise a series of blades radiating from a common center and having rectangular cross sections, together with means for 30 simultaneously rotating the blades, the blades appearing as fine lines when their edges are presented to the observer and as relatively broad lines when the sides of the blades are visible to the observer. Unless 35 considerable care is taken with the placing of the apparatus with respect to the daylight through windows or doors or artificial light in the room, it is possible for the blades at some point of their rotation to reflect said lights from the blades to the eye 40 of the observer, which will give a different color value to the blades reflecting the light. The improved apparatus of the type disclosed also prevents the halation of light especially in the background which gives a 45 different color value to the blades. It is the object of the present invention to provide a meridian dial which embodies the same principle as that disclosed in my co-pending application but in which provision is made for eliminating the possibility of light reflection from the blades and the halation from lights. For this purpose each 50 blade is formed in two portions, which portions are relatively movable from an initial position, in which they lie flat against or in

contact with each other, to a position in which they make equal angles with the observer's line of vision, the result being that the observer looks into a V-shaped groove 60 from the walls of which no light can be reflected toward his eyes. The V-shaped groove also intensifies the blackness of the lines by preventing halation, glow or absorption of light from the illuminated areas. 65

The invention may be embodied in various forms of apparatus and in the accompanying drawings one form is illustrated by way of example and will be described in detail. 70

In the drawings:

Fig. 1 is a front elevation of the apparatus the blades being adjusted to appear of minimum size;

Fig. 2 is a similar view of portion of the apparatus showing the blades adjusted to 75 appear of maximum size;

Fig. 3 is a side elevation of portion of the blade operating mechanism;

Fig. 4 is a section on line 4-4 of Figure 1 to a larger scale; and 80

Fig. 5 is a section on line 5-5 of Figure 4 showing in full and dotted lines the extreme blade positions.

The frame of the dial comprises essentially three semi-circular concentric members 10, 85 11 and 12 secured together by cross members 13 and 14 at their lower ends. The blades are disposed between members 10 and 11 and radiate from a single central point 15, being spaced at intervals of 5° of arc 90 from each other. Each blade comprises two portions 16 and 17 substantially equal in length and in cross section, one blade portion being, however, somewhat broader than the other, as shown in Figure 5. Blade portion 16 has its ends secured to spindles 18 and blade portion 17 has its ends secured to bushings 19, the spindles 18 being rotatably supported in bushings 19, and the bushings 19 being rotatably supported in the frame 95 members 10 and 11. Integral with each upper bushing 19 is a gear segment 20, and secured to the upper end of each spindle 18, by means of an adjusting screw 21, is a second gear segment 22. From Figure 3 it will 100 be seen that these gear segments are so cut away that they may be rotated relatively to each other through substantially an angle of 90°. As each gear segment is connected to a blade portion it follows that the blades 105 may be swung apart until they make substantially an angle of 90° with each other, 110

as shown in dotted lines in Figure 5, or may be folded against each other, as shown in full lines in this figure.

For effecting the simultaneous rotation of the blades a slotted semi-circular member 23 is provided having oppositely directed sets of teeth 24 which constitute racks engaging the respective segments 20 and 22. Member 23 is secured to frame member 11 by bolts 25, these bolts however, passing through slots 26 in member 23 so that the latter may be longitudinally adjusted. Rotatably secured in the frame is a shaft 28 having mounted thereon a disk 29 provided with a cam slot 30 through which extends a pin 31 secured to the rack member 23. A handle 32 is provided for rotating shaft 28 and it will be seen that rotation of this shaft will effect movement of the rack member 23 and hence swinging of the blade portions.

In use the dial is usually placed in front of an illuminated field, which field may be artificially illuminated or may be a natural field such as the sky. The observer is so placed that he looks into the grooves formed when the blade portions are swung apart, which grooves appear perfectly black, it being impossible for the light coming from behind the dial to be reflected from the inner surfaces of the blades and hence there is no possibility of there being any variance in color between the several blades.

To one skilled in the art it will be apparent that the invention may be carried out in various forms of apparatus and is not limited to the exact form shown and described.

Having thus described my invention, what I claim as new and desire to secure by Letters Patent is:

1. An astigmatic dial including in combination, a support, a plurality of blades, mounted on the support and radiating from a common center, the blades being formed in portions relatively movable to cause them to appear to an observer as lines which vary in width.

2. An astigmatic dial including in combination, a support, a plurality of blades, mounted on the support and radiating from a common center, each blade being formed in two portions openable and closable to cause them to appear to an observer as lines which vary in width. 50

3. An astigmatic dial including in combination, a support, a plurality of blades, mounted on the support and radiating from a common center, each blade being divided longitudinally into two parts, relatively rotatable substantially about a common axis, 60 to cause it to appear to an observer as a line of varying width. 55

4. An astigmatic dial including in combination, a support, a plurality of blades, mounted on the support and radiating from a common center, the blades being formed in portions relatively movable to cause them to appear to an observer as lines which vary in width, and means mounted on the frame for rotating said blades. 65 70

5. An astigmatic dial including in combination, a support, a plurality of blades, mounted on the support and radiating from a common center, each blade being divided longitudinally into two parts each part of 75 rectangular cross section, and the two parts being relatively rotatable, so that they may be caused to appear to an observer as lines of varying width.

6. Eyetesting apparatus including in combination, a support, a blade mounted on the support and formed in two portions, operable and closable to cause the blade to appear to an observer as a line of varying width. 80 85

7. Eyetesting apparatus including in combination, a support, a blade mounted on the support and formed in two relatively movable portions so that it may be caused to appear to an observer as a single line of 90 varying width.

In testimony whereof I hereunto affix my signature.

WILLIAM P. REAVES.
